 a corporation of Delaware

Application October 30, 1944, Serial No. 561,141

2 Claims. (Cl. 264—15)

1

This invention relates to centrifugal actuators such as may be employed on motor shafts to open or close switches in response to rotation of the shaft above a certain speed.

An object of the invention is to provide a particularly simple, inexpensive, and reliable actuator of the type referred to.

Another object is to provide an actuator the parts of which can be very easily and quickly assembled and disassembled.

Still another object is to provide a centrifugal actuator which is substantially immune to injury or damage by rotation at excessive speeds.

Other more specific objects and features of the invention will appear from the detailed description to follow of a particular embodiment of the invention.

Briefly, the invention comprises, in its preferred form, an open-ended cup-shaped body or frame mounted on the end of the shaft to be rotated, and containing an axial shiftable pin which is adapted to engage the switch plunger or other member to be actuated. When the cup is not rotating, the pin is maintained in an outer, or projected position, by a spring. Adjacent its open end, the cup-shaped frame has diametrically opposite slots that extend radially and longitudinally and guide a pair of bellcrank levers, the levers being fulcrumed on a spring wire ring which is expanded into an annular groove in the inner surface of the cup-shaped frame. Each bellcrank lever has a long arm extending substantially parallel to the axis of rotation and a short arm extending radially inwardly into contact with the front end of the axially shiftable pin, to oppose the force of the spring. When the device is at rest, there are no centrifugal forces involved, and the spring maintains the pin in an outer position in which the long arms of the levers are approximately parallel to the shaft and are largely contained within the slots in the frame. However, when the shaft bearing the actuator is rapidly rotated, the centrifugal force developed in the long arms of the levers swings them outwardly about their fulcrums, and the short arms of the levers force the axially shiftable pin inwardly, overcoming the force of the spring. The device is most commonly used to actuate a controlled element of a switch, which controlled element is in contact with the end of the axially movable pin and is depressed by the pin when the actuator is stationary. When the actuator rotates at sufficient speed, the pin therein is retracted by the levers, permitting the plunger of the switch to be ejected by a spring

2

in the switch mechanism. It is preferable in such devices that the actuator mechanism be completely out of contact with the control switch when the actuator is rotating, to eliminate any friction between the parts.

In the drawing:

Fig. 1 is a view showing an actuator in accordance with the invention mounted on the end of a motor shaft for actuating the plunger of a

10 switch;

Fig. 2 is a view of the actuator similar to the view of Fig. 1, but showing the position of the actuator when rotating.

Fig. 3 is a cross section taken substantially in 15 the plane III—III of Fig. 1; and

Fig. 4 is a detail section taken in the section IV—IV of Fig. 3.

Referring first to Fig. 1, there is shown a motor 10, of any desired construction, having a 20 shaft 11 on the outer end of which is mounted an actuator 12 in accordance with the present invention, for actuating the plunger 13 of a switch 14.

The actuator 12 comprises a tubular body, or 25 frame, 15 having a central bore 16 therein. The rear end of this bore 16 receives the outer end of the motor shaft 11, and the body 15 may be secured to the shaft for rotation therewith by a pin 17.

30 The bore 16 extends forwardly for a substantial distance beyond the end of the motor shaft 11 and serves as a guide for a plunger or pin 18 having a head 19 on its outer or front end. A helical compression spring 20 surrounds the pin 18 and is compressed between the body member 35 and the head 19 of the pin, to constantly urge the latter axially to the right out of the bore 16. Outward movement of the pin 18 by the spring 20 is limited by a plurality of bellcrank 40 lever elements 22 which are guided for movement in radial slots 15a provided therefor in the frame 15. Each lever element 22 has a long arm 23 extending substantially parallel to the axis of the body 15, and a short arm 24, which is 45 substantially normal to the long arm 23 and extends inwardly into engagement with the front face of the head 19 of pin 18.

All of the lever elements 22 are fulcrumed on 50 a spring wire ring 25 which is positioned in an annular groove 26 formed within the skirt portion of the body 15, each lever element having an aperture 27 for receiving the wire 25. As best shown in Figs. 3 and 4, the wire ring 25 is not continuous but is split and originally shaped to a larger diameter than the groove 26 in which it

is mounted, so that it can be readily assembled and expands into the groove. The resilience of the wire ring always maintains it in position within the groove because all forces applied to the ring by the lever elements act either outwardly or longitudinally, never inwardly. One end of the ring is preferably turned in as indicated at 28 to prevent the ring from shifting in the groove and releasing the lever elements, although in use there is little or no tendency for the ring to shift.

The device can be very readily assembled and disassembled by virtue of the fulcrum structure involving the ring 25 in the groove 26. Thus, the procedure for assembling the parts of the actuator together is to first place the helical compression spring 20 about the pin 18 and insert the latter in the bore 16 far enough to fully compress the spring. Thereafter, the lever elements 22 are threaded on to the fulcrum ring 25, and the levers and ring are assembled on the body 22 by sliding the long arms 23 of the lever elements longitudinally into the radial slots in the body while at the same time squeezing the ring 25 radially (with the ends of the ring in overlapping relation) to enter the ring into the open end of the skirt of the body. As soon as the ring has been entered into the skirt, it is retained against expansion by the skirt; the ring and the lever elements are then pressed axially until the ring reaches the groove 26 and snaps into it. Thereafter, the pin 18 will be prevented from escaping from the bore 16 by engagement of the head of the pin against the short arms 24 of the lever elements.

As shown in Fig. 1, the plunger 13 of the switch 14 is engaged by the head 19 of pin 18 and slightly depressed thereby, in which position the contacts of the switch 14 will be either open or closed according to the design of the switch. However, when the actuator is rotated above a predetermined speed, the centrifugal force developed in the long arms 23 of the levers 22 throws them outwardly as shown in Fig. 2, in which position the short arms 24 of the lever elements depress the pin 18, permitting the plunger 13 of the switch to be lifted by a spring (not shown) within the switch 14 and close or open the contacts within the switch, depending upon the construction of the latter. Switches of the type shown are old and well-known and do not constitute a part of the present invention. Preferably, the movement of the pin 18 by the lever elements 22 is sufficient to disengage the head 19 of the pin from the switch plunger 13 so that there is no friction therebetween during rotation of the actuator, after the motor has come up to speed.

As shown in Fig. 2, depression of the pin 18 and outward movement of the long arms 23 of the lever elements is limited by contact between the end of the neck 30 of the body at the outer end of bore 16 and the head 19.

Various departures from the exact construction shown can be made without departing from the invention which is to be limited only to the extent set forth in the appended claims. As ex-

amples of changes that can be made, more than two levers 22 may be employed where greater force is required. It is desirable, however, in order to produce a balanced structure, that the lever arms be symmetrically positioned about the axis of rotation.

I claim:

1. A centrifugal actuator of the type described comprising: a tubular frame member supported for rotation about its axis and adapted to be rotated; a controlled element axially aligned with said axis and supported for axial movement with respect to said frame member; spring means urging said controlled member axially in one direction with respect to said frame member; a plurality of bellcrank lever elements fulcrumed to said frame member for movement in radial planes, each lever element having a first arm normally extending approximately parallel to said axis and a second arm approximately normal to the first arm and extending inwardly into engagement with said controlled element for moving the latter against the force of said spring means in response to outward movement of said first arm; said tubular frame member comprising an annular skirt surrounding said controlled element and said skirt having an annular groove in its inner surface and having radial longitudinal slots intersecting said annular groove for slidably receiving said lever elements; said lever elements having transverse bearing holes therein; and a ring in said groove and extending through said bearing holes in said lever elements for fulcruming said lever elements on said frame member.

2. A centrifugal actuator of the type described comprising: a tubular frame member supported for rotation about its axis and adapted to be rotated; a controlled element axially aligned with said axis and supported for axial movement with respect to said frame member; spring means urging said controlled member axially in one direction with respect to said frame member; a plurality of bellcrank lever elements fulcrumed to said frame member for movement in radial planes, each lever element having a first arm normally extending approximately parallel to said axis and a second arm approximately normal to the first arm and extending inwardly into engagement with said controlled element for moving the latter against the force of said spring means in response to outward movement of said first arm; said tubular frame member comprising an annular skirt surrounding said controlled element and said skirt having an annular groove in its inner surface and having radial longitudinal slots intersecting said annular groove for slidably receiving said lever elements; said lever elements having transverse bearing holes therein; and a split spring wire ring positioned in said groove and extending through said bearing holes in said lever elements for fulcruming said lever elements on said frame member; said ring being originally of larger diameter than said annular groove whereby it is resiliently retained in said groove.

CHARLES E. MILLER.
